UNITED STATES PATENT OFFICE.

THOMAS J. POTTER, OF LOS ANGELES, CALIFORNIA.

DESIGN FOR A GAS-RADIATOR.

53,525.

Specification for Design.

Patented July 8, 1919.

Application filed July 1, 1918. Serial No. 242,951. Term of patent 14 years.

To all whom it may concern:

Be it known that I, THOMAS J. POTTER, a citizen of the United States, residing at Los Angeles, in the county of Los Angeles and State of California, have invented a new, original, and ornamental Design for Gas-Radiators, of which the following is a specification, reference being had to the accompanying drawing, forming part thereof.

The drawing is a perspective view of a gas radiator embodying my invention.

I claim:

The ornamental design for a gas radiator, as shown.

THOMAS J. POTTER.

Witnesses:

LOUIS W. GRATZ,
DOROTHY MOORHOUSE.
